UNITED STATES PATENT OFFICE.

ALFRED RYAN, OF ANNIESLAND, GLASGOW, SCOTLAND, ASSIGNOR TO THE IODO RUBBER & WATERPROOFING COMPANY, LIMITED, OF GLASGOW, SCOTLAND, A BRITISH COMPANY.

RIGID AIRSHIP.

Application filed September 15, 1927, Serial No. 219,716, and in Great Britain September 17, 1926.

This invention relates to rigid airships.

At the present time the outer cover or envelope of an airship is constructed of large sheets or panels and is usually maintained taut by the combined use of dope and a system of closely pitched lacing. This method does not provide satisfactory means of controlling the initial tautness of the cover and proves inconvenient when fitting or removing any portion of the cover. When it is desired to obtain access to the interior of the airship it is necessary to undo the lacing so as to loosen or remove one or more panels of the outer cover. The effect of removing a panel, in cases where the usual system of lacing is adopted, produces sagging of the various panels contiguous to the panel which has been removed, and the object of the present invention is to enable the outer cover to be constructed in convenient sections that can be easily fitted or removed without interfering with the main body of the cover. Other objects are to provide a ready means of applying the initial tautness to the main body of each section and to apply the main loads, due to the tautness of the cover at those points, to the framework where the loads can readily be estimated by calculation.

According to the present invention the sheets or panels of the outer cover are subdivided into comparatively small and approximately rectangular sections and four or more catenaries are provided which are sewn or otherwise attached to each section or panel towards each edge thereof, the ends of the catenaries being attached through the intermediary of turnbuckles or their equivalent, to the rigid framework of the airship preferably at the points where the longitudinal girders are intersected by the transverse frame members. Any desired degree of tautness can initially be imparted to the section or panel by means of the turnbuckles or their equivalent attached to the catenaries and thereafter the edges of each panel or section are laced or otherwise attached to the edges of contiguous sections.

In order that the said invention may be clearly understood and readily carried into effect the same will now be described more fully with reference to the accompanying drawing, which shows diagrammatically at Figure 1 a section or panel constructed ac-

cording to one embodiment of the present invention, and

55

Figure 2 is a detail on an enlarged scale showing one corner of the said panel.

60

A is one of the approximately rectangular sections or panels forming part of the outer cover of a rigid airship of polygonal cross section the section being of such a size that it corresponds approximately to the space which is formed between the points of intersection of two contiguous longitudinal girders and two contiguous transverse frame members. B, B, are four catenaries which, in the example shown, are constituted by a rope of hemp or wire attached to the outer edge of the inner portion A' of the section, the outer portion A² of the section being attached to the inner portion A' by lacing or stitching A³. The rope B is formed into loops B', B' towards each corner of the section and by means of ropes C, C, each provided with a turnbuckle C' the section is attached to the framework of the airship at the points where the longitudinal girders and transverse frame members intersect one another. By means of the turnbuckles C' any desired degree of tautness can initially be imparted to the section A and thereafter the edges of section A are attached by lacing or otherwise at the points A⁴, A⁴ to the edges of contiguous panels.

70

Owing to this arrangement and when it is desired to obtain access to the interior of the airship, the lacing of the section which it is desired to remove is loosened at the points A⁴, A⁴ and thereafter the section is disconnected from the framework of the airship by unscrewing the turnbuckles C', C'. The entire section can then be removed. Owing to the provision of the catenaries B, B and the turnbuckles C', C' which maintain each section separately under tension the removal of a section or sections, does not produce any sagging of contiguous sections. The present arrangement also reduces flapping by placing each section of the outer cover under tension. Furthermore, the use of catenaries enables the operation of doping the outer cover to be completed mainly or entirely prior to the section being placed in position on the airship.

95

In the example shown the section A is fitted with four tensioning members or

catenaries but further members may be fitted in a similar manner, of example, four additional members having a different curvature may be fitted as shown in dotted lines at 5 Figure 1.

What I claim and desire to secure by Letters Patent of the United States is:—

1. A method of attaching the outer cover to a rigid airship which consists in constructing the outer cover in comparatively small and approximately rectangular sections or panels, each section or panel being provided with four or more catenaries which are attached thereto towards each edge thereof and the ends of the catenaries being connected to the framework of the airship, preferably at the points where the longitudinal girders are intersected by the transverse frame members, through the intermediary of 15 turnbuckles or their equivalent.

2. A method as claimed in claim 1, where-

in the edges of each panel or section are laced or otherwise attached to the edges of contiguous sections after any desired degree of initial tautness has been imparted to the 25 section or panel by means of the turnbuckles or their equivalent.

3. An airship provided with an outer cover which is constructed in rectangular sections and in which each section has four 30 or more catenaries whose ends are attached to the rigid framework of the airship through the intermediary or turnbuckles or their equivalent.

4. A detachable section for the outer cover 35 of an airship provided with catenaries towards each edge thereof and with turnbuckles or other tautening devices for attaching the catenaries to the framework of the airship.

A. RYAN.
